ELECTROMAGNETIC RELAY

Benjamin W. Brion, Minneapolis, Minn., assignor
to Minneapolis-Honeywell Regulator Company,
Minneapolis, Minn., a corporation of Delaware

Application April 16, 1948, Serial No. 21,481

9 Claims. (Cl. 175—339)

1

My invention relates to electromagnetic relays and more particularly to polarized relays of the direct current type.

An object of this invention is to provide an improved polarized relay which is extremely sensitive in operation yet rugged in construction.

It is an object of this invention to provide a relay design which is simple in construction and the parts of which may be readily fabricated by stamping operation.

It is further an object of this invention to provide an easily adjustable relay.

Another object of this invention is to provide a polarized relay in which a minimum of adjustment and maintenance is required.

Still another object of this invention is to provide a relay which is compact and economical to manufacture.

A further object of this invention is to provide a relay with an improved contact structure in which maximum life and good electrical contact is insured.

It is further an object of this invention to provide a polarized relay in which the polarizing magnets are readily interchangeable.

Other objects of this invention will become apparent upon a study of the following specification and drawings wherein:

Figure 1 is a plan view of the relay;

Figure 2 is a side elevation view of the relay with parts broken away;

Figure 3 is a right end elevation view of the relay as shown in Figure 1;

Figure 4 is a left end elevation view of the relay as shown in Figure 1.

The electromagnetic or polarized relay disclosed in Figures 1 through 4 is mounted on a base member 10 composed of an insulating material, preferably "Bakelite" or other similar plastic material. Base member 10 is a molded structure having a substantially square lower or base surface 11, two upstanding portions 12 and a contact supporting portion 13 attached to or formed integral with one of the upstanding portions 12. A cavity 14 or recess is formed in base member 10 between the upstanding portions 12 in which is positioned the magnetic core structure 15 of the relay. The contact mounting portion 13 abutting one of the upstanding portions 12, as seen in Figure 2, houses the stationary contact structure 16 for the relay. Terminals 17 and 18 positioned on the upper and lower surfaces of this mounting portion provide a means for connecting to the stationary elements

2

of the stationary contact structure 16 in a manner later to be described. A U-shaped notch 19 and holes 20 in the lower surface 11 of base member 10 provides a means for attaching said base member to any particular surface desired in any suitable manner.

The magnetic core structure 15 positioned in the recess 14 formed in base member 10 by the upstanding portions 12 includes a pair of identical U-shaped core members 23, 24 of magnetic material such as nickel iron alloy. The core members 23, 24 have at their extremities transversely extending pole pieces 25, 26 respectively which are integral with said core members. Similarly each core member 23, 24 has an extending L-shaped magnet mounting bracket portion 27, 28, respectively, located equi-distant between the pole pieces 25, 26 of each core member. The free extremities of these magnet mounting bracket portions have tapped holes therein for purposes later to be described. Core member 24 is positioned in the recess 14 of base member 10 such that its pole pieces 26 rest on the upstanding portions 12 of said base member and within slots in said upstanding portions 12 not shown in the drawing. The upper core member 23 is positioned with its pole pieces 25 in near abutting relationship to the pole pieces 26 of core member 24 and with the main portion of the core member extending in the opposite direction from that of core member 24. The magnet mounting bracket portion 27 is disposed in the same direction as that of portion 28 of core member 24 such that the extremities thereof lie in the same plane. Positioned between the pole pieces 25 and 26 of core members 23, 24 respectively, are a pair of U-shaped spacer members 31 of non-magnetic material. These spacer members, in addition to their general configuration, are bent at their open extremity such that that portion will lie parallel with the pole pieces 25, 26 and are bent at the closed extremity such that that portion will be disposed away from the upper core member 23. The bifurcated portion of each spacer member 31 fits around a reduced portion 32 of upper core member 23 and underneath the pole pieces 25. A pair of air gaps 33 are defined by the positioning of the spacer members 31 between the pole pieces 25, 26 which air gaps are limited in one direction by the pole pieces 25, 26 and in the other direction by the bifurcated ends of the spacer members 31. Brackets 33, 34 secure the spacer members 31 and the upper core member 23 as well as lower core member 24 in position within the

slots or notches in the upstanding portions 12 and the cavity 14 therebetween. The brackets are made of a non-magnetic material and are secured to the upstanding portions 12 of base member 10 by screws 35 which mount into tapped holes in the upstanding portions. Bracket 34 differs from bracket 33 in that it has an upstanding flange portion 36 attached thereto with a tapped hole 37 therein, the purpose of which will be later described. Also assisting in the positioning of core members 23, 24 with respect to one another is a permanent magnet 40 which is attached to the magnet mounting bracket portions 27, 28 respectively of said members. Magnet 40 has preferably notches at either extremity and is secured to the bracket portions 27, 28 by screws 41 which fit into tapped holes in the bracket portions. Core members 23, 24 and magnet 40 form a cavity or opening in the magnetic core structure 15 within which is mounted coil or winding 45 which is wound on a bobbin 46 of insulating material. Bobbin 46 has an aperture 47 therethrough which is somewhat larger in cross dimension than the air gaps 33 such that an armature 50 which is positioned therethrough will not engage the bobbin.

Armature 50 is a rod-like member of high permeability magnetic material which is rectangular in cross-section and which cross-section is reduced from that of the air gap 33 and aperture 47 of bobbin 46. It is pivoted on a mounting structure 52 located outside of the magnetic core structure 15 and secured to base member 10. The pivoted extremity of armature 50 has a portion 53 bent normal thereto at which point a flexible plate 54 is attached, as by rivets 56, the flexible plate or reed 54 being positioned between the bent portion 53 of the armature 50 and a non-magnetic backing plate 55 over which the rivets 56 are bent to make a secure and positive connection between the armature 50 and flexible plate or reed 54. Armature 50, flexible plate or reed 54 and backing plate 55 are all made of good electrical conductive material for purposes to be later noted. The flexible member or reed 54 is bifurcated at its lower extremities which bifurcations 60 are attached to an adjustable mounting plate 61 and a terminal plate 62 in any suitable manner such as by rivets 63 shown herein. The bifurcations 60 are placed between adjustable mounting plates 61 and terminal plate 62, all of which members are made of a good electrically conductive material, for purposes to be noted later. Plate 61 is positioned in a slot 65 of base member 10 extending from the lower surface 11 along one of the upstanding portions 12, as can be seen in Figure 3. Plate 61 includes notches 66 therein through which mounting screws 67 are positioned into tapped holes in the base member. As determined by the notches 66, the adjustable plate 61 may be moved up and down within the slot 65 to position the structure mounted thereon and hence armature 50 within the air gap 33 of core structure 15. The free or upper end of flexible reed or plate 54 is also bifurcated as at 70 best shown in Figure 3. A screw 71 is positioned in this bifurcation and engages the tapped aperture 37 of mounting bracket 34 such that the position of this bifurcated end of reed 54 may be varied, hence biasing the armature 50 in a downward direction. As shown in Figure 2, the adjustable mounting plate 61 is so positioned on base member 10 that armature 50 is located nearest the pole piece 25 of core member 23 at the pivoted

extremity thereof. Similarly, adjustable screw 71 is positioned against the flexible member 54 at the bifurcated extremity 70 to bias the armature downward at its unpivoted extremity into engagement with its stationary contact structure 16.

Armature 50 at its unpivoted extremity carries contact 75 which engages contacts 76, 77 of the stationary contact assembly 16, as can best be seen in Figures 2 and 4. Stationary contact structure 16 which is attached to the base member 10 at the contact mounting portion 13 includes contact frames 78, 79 attached to said mounting portion 13 by terminal screws 17, 18, respectively. An opening 80 is positioned in the contact mounting portion 13 of base member 10 for the purpose of housing the contact structure 16 as well as giving access to that portion for mounting and assembly of said contact structure. The terminal 17 is actually a screw which extends through a portion of the contact mounting portion 13 into opening 80 such that contact frame 78 may be positioned thereon and a nut and washer 81 threaded over the screw to secure said contact frame to the base member. Similarly, contact frame 79 is secured to the contact mounting portion 13 by means of terminal 18 whose threaded portion extends into opening 80 where an apertured end of contact frame 79 is positioned thereon and a nut and washer threaded onto the terminal screw to secure the frame. The contact frames 78 and 79 are attached to the contact mounting portion 13 of base member 10 near the extremity of said upstanding portion and the aperture 80 therein. These frames extend in the longitudinal direction of the upstanding portion 12 of base member 10 and aperture 80 being disposed substantially parallel to one another and to either side of that portion of armature 50 which carries the movable contact 75. Frame members 78, 79 have attached thereon flexible contact carrying reeds 83, 84, respectively, which carry the stationary contacts 76, 77 respectively. Contact carrying reeds 83, 84 are disposed on that side of their respective contact frames which lies away from the armature 50 and are attached thereto in any suitable manner as by rivets 85. The reeds 83, 84 are bent along their extremity such that the free end is biased into engagement with the contact frame. Positioned at these free ends of contact carrying reeds 83, 84 are the stationary contacts 76, 77 respectively which are attached to the reeds by pin-like rivets. The pins carrying the contacts extend through holes in the respective contact frames 78, 79 such that the reed is positioned on one side of the contact frame and the contact member which it mounts is positioned on the other side of the contact frame. Stationary contacts 76, 77 are aligned on the contact frames 78, 79 respectively to be engaged by the movable contact 75 carried on armature 50. The free ends of contact frames 78, 79 have an additional aperture or hole 86, 87 respectively therein into which the pin-like tips 88, 89 of adjustment screws 92, 93 extend. The adjustment screws 92, 93 are threaded through tapped holes in the contact mounting portion 13 of base member 10 and extend into the opening 80, to engage the free ends of the contact frame members. These screws work against the rigidity or bias of the frame members to position said members into desired proximity with the contact carrying armature 50. The frame members 78, 79 do not engage the

armature, however, since stationary contacts 76, 77 are positioned between the armature and frame and upon engagement of the movable contact 75 with either of these contacts, the latter move against the bias of their respective mounting reeds a limited distance provided by the pin-like mounting rivets to absorb armature inertia and provide for wipe of the contacts.

The operation of the present relay is conventional for a polarized relay utilizing a direct current actuating winding or coil. Magnet 40 of the present relay is attached to the core members 23 and 24 in such a manner that the upper end of the magnet is of south polarity and the lower end of the magnet is of north polarity and hence pole pieces 25 are magnetized to a south polarity and pole pieces 26 to a north polarity. Similarly, coil 45 is so wound and positioned in the cavity of core structure 15 that it magnetizes armature 50, when energized, with a south polarity near its pivoted extremity and a north polarity near its contact carrying or free extremity. As was previously noted the armature is positioned in the air gaps 33 of the core structure 15 in such a manner that it is closer to the upper pole piece 25 at the pivot end in the air gap of the pivoted extremity and closer to the lower pole piece 26 in the air gap at the unpivoted extremity. Similarly flexible reed 54 is biased by compression through adjustment screw 71 and a tapped hole 37 of flange 36 to bias the armature 50 toward the pole piece 26 at the unpivoted extremity. With coil 46 de-energized, armature 50 is affected by two conditions to hold it in a predetermined position, that is, with movable contact 75 engaging stationary contact 77. These conditions biasing the armature in the normally deenergized position are the bias of flexible reed 54 and the magnetic pull created by the permanent magnet 40. The flux in the magnetic core structure due to magnet 40 alone will tend to circulate directly across the air gaps 33 but a portion of this flux due to the proximity of the armature to pole piece 25 at the pivoted extremity and pole piece 26 at the unpivoted extremity will pass through the armature itself tending to draw the armature toward the lower pole piece at the unpivoted extremity. As coil 45 is energized with a direct current of a particular polarity, a flux will be built up in the magnetic circuit and a definite polarity will be established at or near the extremities of the armature. This polarity will be such that a north pole will be created near the unpivoted extremity and a south pole near the pivoted extremity and the attraction between the armature and the upper pole 25 having a south polarity at the unpivoted extremity will be such to cause the armature to move away from engagement of contacts 75, 77 into engagement with contacts 75, 76. This type of operation will be a snap action since the magnetic pull created by the flux in the armature will be larger than that created by the permanent magnet. After the armature 50 has moved to the upper position, that is with contacts 75, 76 made, the flux caused by the energization of coil 45 will tend to circulate through the upper core member 23 and armature 50. This circulating flux will tend to hold the armature in its newly acquired position with sufficient contact pressure to establish a good electrical circuit between the contacts.

Similarly, as energization of coil 45 is decreased, this circulating flux will decrease to a point where the effect of the biasing spring will overcome the magnetic pull caused by it and the armature will

be moved away from engagement of contacts 75, 76. At this point, the energization of the magnetic circuit due to the magnet 40 alone is such as to move the armature into engagement with contact 75, 77 with a similar snap action and sufficient contact pressure will be had at these contacts due to the effective magnetic pole and bias of the reed 54.

The electrical circuits for this relay are conventional inasmuch as all parts of the contact structure are made of good electrically conductive material. Circuits are established from stationary contacts 76, 77 to terminals 17 and 18 respectively through their respective reeds and contact frames. Similarly contacts 75 are connected to the terminal plate 62 through a circuit formed by the armature itself, the flexible reed 54, and the terminal point 62.

While I have illustrated the preferred embodiment of my invention, it is obvious that many other modifications or adaptations of this improved relay will occur to those skilled in the art. Therefore it should be clearly understood that the invention is to be limited only by the scope of the appended claims.

I claim as my invention:

1. A polarized relay comprising, in combination: an insulated base member having a recess therein; a magnetic core structure including a pair of U-shaped core members of magnetic material having pole pieces at either extremity thereof and transversely extending magnet mounting bracket portions integral therewith located equi-distant between said pole pieces; a pair of U-shaped spacer members of nonmagnetic material; one of said core members being positioned in said recess of said base member, the other said core members being positioned with its pole pieces in near abutting relationship to the pole pieces of said first named core member and with said magnet mounting bracket portion extending in the same direction as that of the first named core member; said spacer members being positioned between the pole pieces in said near abutting relation to define an air gap at either extremity of said core structure; bracket means securing said core members and said spacer members in a fixed relation to said base member at either extremity of said core structure; a bar type permanent magnet mounted between said magnet mounting bracket portions and removably secured thereto; a rod-like armature of magnetic material positioned to extend through said air gaps and between extremities of said U-shaped spacer members, said armature being mounted on a pivot structure located outside said core structure; said pivot structure including a flexible reed to which said armature is attached and an adjustable mounting plate mounted on said base member carrying said reed; said armature being positioned through said adjustable plate closer to one of the pole pieces of the pair defining the air gap nearest the pivoted extremity thereof to magnetically bias said armature into a predetermined position; means including a flange attached to one of said bracket means adapted to adjust said flexible reed and further bias said armature into said predetermined position; and a winding encircling said armature and disposed within said core structure, said winding when energized magnetizing said armature and causing it to be displaced from its predetermined position.
2. In a relay, a magnetic core structure po-

sitioned on a base member of insulating material, said core structure including a pair of core members with pole pieces at the extremities thereof and a permanent magnet bridging said core members, said core members being positioned with said pole pieces in near abutting relationship, nonmagnetic bifurcated spacer members positioned between said pole pieces to define an air gap therebetween, an armature positioned in said air gap and pivoted on a mounting structure external of said core structure for movement between the bifurcated portions of said spacer members, said armature mounting structure including a flexible reed to which said armature is secured and an adjustably mounted plate to which said reed is secured, said reed having an extending portion cooperating with an adjustable screw means secured to said base member for biasing said armature into a predetermined position, and coil means encircling said armature and positioned within said core structure.

3. A polarized relay comprising a magnetic core structure mounted in a recessed base member, said core structure including a pair of core members with pole pieces in near abutting relationship to one another to define a pair of air gaps therebetween, nonmagnetic bifurcated spacer members positioned between said pole pieces to accurately define said air gaps, non-magnetic bracket means securing said core structure including said core members and said spacer members to said base member, one of said bracket members having an extending flange therefrom with an adjusting means mounted therein, a permanent magnet bridging said core members to establish a polarity in said pole pieces, a pivotally mounted armature positioned in said air gaps for movement between the bifurcated portions of said spacer members, said armature including an extending reed-like biasing member which cooperates with said adjusting means of said flange on said one of said bracket members, and a coil encircling said armature and positioned in the recess of said base member.

4. In a relay, a magnetic core structure having a pair of fixed air gaps therein including an energizing means mounted on a base, and an armature cooperating with said core structure positioned in said air gaps and pivotally mounted on an armature mounting structure attached to said base, said armature mounting structure including a flexible reed to which said armature is secured and a plate mounted on said base to which said reed is secured, said reed having an extending portion with an adjustable screw means therein which cooperates with said base to bias said armature into a predetermined position, said plate being adjustable to vary the position of said armature within said air gaps of said magnetic core structure.

5. A polarized relay comprising in combination: an insulating base member having a recess therein; a magnetic core structure including a pair of U-shaped core members of magnetic material having pole pieces at either extremity thereof and a transversely extending magnet mounting bracket portion integral therewith located equidistant between said pole pieces, a pair of U-shaped spacer members of nonmagnetic material; said core members being placed one on top of another into said recess in said base member with said spacer members disposed between the pole pieces of said members to define a pair of air gaps at the extremities of

said core structure and a coil receiving cavity therebetween; permanent magnet means connected between said magnet mounting bracket portions to energize said pole pieces with definite magnetic polarities, a bar type armature of magnetic material disposed within said air gaps between the extremities of said spacer members and pivotally mounted on an adjustable reed type mounting structure located on said base member external of said core structure to be nearer one than the other of said pole pieces of said pair forming the air gap nearest the pivotal mounting; said magnet means setting up magnetic polarities in said pole pieces to bias said armature toward said lower pole piece at the unpivoted extremity of said armature; and a coil surrounding said armature and positioned within said cavity in said core structure to magnetize said armature and overcome the bias created by said permanent magnet means.

6. In a relay, a base of insulating material having a recess therein, a magnetic core structure positioned in said recess, said core structure including a pair of U-shaped core members having pole pieces at the extremities thereof and a magnetic energizing member bridging said core member to set up fixed magnetic polarities in said pole pieces, said core members being positioned with said pole pieces in near abutting relationship and with non-magnetic bifurcated spacer members therebetween to define with said pole pieces a pair of air gaps, a bar type armature positioned within said pair of air gaps and pivotally mounted for movement between said abutting pole pieces from a point outside of said core structure, adjustable biasing means attached between said armature and said base member, flexible means mounting said armature for pivotal movement, said mounting means being attached to said base member and movably adjustable relative thereto to vary the position of said bar type armature within said air gaps and between said pole pieces, and a coil encircling said armature and positioned within said core structure.

7. In a relay, a magnetic core structure positioned on a base member of insulating material, said core structure including a pair of core members with pole pieces at the extremities thereof and a permanent magnet bridging said core members, said core members being positioned with said pole pieces in near abutting relationship, non-magnetic bifurcated spacer members positioned between said pole pieces to define an air gap therebetween, an armature positioned in said air gap and pivoted on a mounting structure external of said core structure for movement between the bifurcated portions of said spacer members, said armature mounting structure including a flexible reed to which said armature is secured and an adjustable mounting plate to which said reed is secured, said plate being mounted on said base member, adjustable biasing means attached between said base member and said armature for biasing said armature into a predetermined position, and coil means encircling said armature and positioned within said core structure.

8. In a relay, a magnetic core structure positioned on a base member of insulating material, said core structure including a pair of core members with pole pieces at the extremities thereof and a permanent magnet bridging said core members, said core members being positioned on said base member with said pole pieces in near

abutting relationship to define a pair of airgaps therebetween, a bar type armature of magnetic material positioned in said air gaps, adjustable means attached to said base member and pivoting said armature from a point external of said core structure for movement between said pole pieces forming said air gaps, flexible reed means included in said adjustable pivoting means for said armature having an extending portion, an adjustable screw means secured to said base and engaging said extending portion of said reed for biasing said armature into a predetermined position, and coil means encircling said armature and positioned within said core structure.

9. In a relay, a magnetic core structure positioned on a base member of insulating material, said core structure including a pair of core members with pole pieces at the extremities thereof and a magnetic energizing member bridging said core members, said core members being positioned with their pole pieces in near abutting relationship, non-magnetic spacer members positioned between said pole pieces to define an air gap therebetween, an armature positioned in said air gap and pivoted on a mounting structure external of said core structure from movement between the pole pieces and in said air gap, said armature mounting structure including a flexible reed to which said armature is secured and an adjustable mounting plate to which said reed is secured, said reed having an extending portion

cooperating with an adjustable screw means secured to said base member for biasing said armature into a predetermined position, and coil means encircling said armature in position within said core structure.
